STRUCTURAL SET

Charles A. Geib and Clarence B. Geib, Chicago,
Ill., assignors to The Norwood Company, Chi-
cago, Ill., a corporation of Illinois

Application August 22, 1938, Serial No. 226,126

2 Claims. (Cl. 46—28)

The invention relates to structural sets.

It is now common practice to provide toy structural sets which include members adapted to be secured together by screws or bolts. In erecting structures with such sets, particularly those composed of a large number of parts, considerable time is required for their assembly.

The object of the present invention is to provide a toy structural set which can be more easily and quickly assembled than one composed of parts adapted to be secured together by screws, and which can be produced at a low cost.

This object is attained primarily by providing the structural parts with tongues and slots which are adapted to be slipped together and readily interlocked to secure them in assembled relation.

Other objects of the invention will appear from the detailed description.

The invention consists in the several novel features which are hereinafter set forth and are more particularly defined by claims at the conclusion hereof.

In the drawings: Fig. 1 is a perspective of a structure embodying one form of the invention. Fig. 2 is a view showing a group of elements separated to illustrate them individually. Fig. 3 is a horizontal section through one of the connecting brackets with a side-bar and an end-bar connected thereto. Fig. 3^a is a vertical section through one of the brackets for supporting a plate or shelf. Fig. 4 is a perspective illustrating a modified form of the invention. Fig. 5 is a perspective of one of the vertical tubular posts and a connecting bracket of the construction shown in Fig. 4. Fig. 6 is a vertical section through a pair of vertically connected posts of the construction shown in Fig. 4. Fig. 7 is a perspective illustrating the parts shown in Fig. 6 separated preparatory to assembling.

The invention is exemplified in Figs. 1 to 3 in a set of metal elements forming a skeleton or self-supporting structure or framework which comprises: sectional standards or uprights built up of bars 10 with rightangle flanges; brackets for connecting the bars 10 of the standards formed of bars 11 having rightangle flanges adapted to fit against and lap the inner faces of the flanges of bars 10, and integral rightangled arms 13 of flat stock fixed to the inner faces of the flanges of bars 11; and bars 12, 12^a, 12^b of flat stock for forming the lateral or horizontal members of the structure of different lengths. The side-faces of the ends of arms 13 and the side-faces of the ends of bars 12, 12^a, 12^b are

adapted to overlap one another to fit together for assembly into the structure. Any number of bars 10 may be assembled with connecting brackets to form a structure of different heights. Any one or number of the bars 12, 12^a, 12^b may be used to form a lateral connecting member between any pair of standards to vary the size and shape of the structure.

All of the overlapping portions of the elements, i. e., bars 10, 11, arms 13, and bars 12, 12^a, 12^b, 10 are provided with interfitting means which makes it possible to assemble them together by inserting the hooks into the slots and relative sliding movement. Each of said connections comprises a pair of slots 15 in one element and a pair of 15 instruck hook-shaped tongues 14 in the other element at the overlapping end-portions of each pair of elements which are to be secured together. These slots permit the hooks to pass through and to be slipped into interlocking engagement with an overlapping element. When the hooks are thus engaged they will force together the contiguous faces of the overlapped elements, hold them against transverse separation, and will also secure them in longitudinal 20 alignment. In order to yieldingly secure the assembled ends of overlapping elements so the hooks 14 will not slide into position so they will be released from slots 15, one of the overlapping elements is formed with a concave socket 17 to 25 receive a convex stud 16 on the contiguous face of the other element. As the hooks 14 are forced into interlocking position, the studs 16 will spring into sockets 17. Studs 16 and sockets 17 are 30 formed by indenting the bars. 35

In the structure shown in Fig. 1, each standard comprises a pair of angle-bars 10 assembled together in superposed relation through an angle-bar 11, the flanges of which fit against the inner faces of the flanges of the angle-bars 10. 40 Each end of the bar 10 is provided with a pair of tongues 14 for coacting with slots 15 in the contiguous flanges of bar 11 and an interfitting stud-connection 16 and 17 so that the bars 10 which form the posts will be secured in vertical or end-to-end alignment. The standards at corners of the structure are connected by flat bars 12^b which are provided at each end with a pair of tongues 14 adapted to pass through slots 15 in the arms 13 of the connecting brackets, and with an interfitting connection 16, 17 to secure the arms and bars against relative longitudinal and transverse movements. The sides of the structure are formed by pairs of bars 12 each provided at both of its ends with a pair of tongues 14 for 50 55

interlocking with slots 15 in the arms 13 of the connecting brackets and an intermediate bar 12^a which is provided at its ends with slots 15 for hooked tongues 14 on the adjacent ends of the bars 12. This forms side-members which may be built to any length desired.

In practice, the set of elements includes a series of angle-bars 10 and a series of flat bars of varying lengths, all of which are provided with continuous series of slots so that structures of different heights, widths and lengths may be selectively assembled. For use in connecting end and side-bars at the top of the structure, some of the angle-bars 11 may terminate so they will be approximately flush with the arms 13, as at 11^a.

To provide a shelf at one side of the structure, angle-brackets of flat stock comprising arms 18 and 19 may be provided. Each of the said arms is provided with a pair of hooked tongues 14, one pair of which is adapted to interlock with slots 14 in a flange of one of the angle-bars 10 and the other of which is adapted to pass through slots 20 in a shelf-plate 21.

The construction described exemplifies one which comprises angle-bars, flat bars and connecting brackets which are adapted to be assembled to form a great variety of structures by means of the interlocking connections between the elements, whereby the elements will be secured together in alignment as desired and which will be rigidly connected transversely and yieldably secured against endwise separation by the interfitting connections 16, 17.

In the construction illustrated in Figs. 4 to 7, the standards are built up of tubular bars 22 and connecting brackets, each provided with short flat vertical bars 23. Each end of bar 22 is flattened, as at 23^a, and provided with a cap 24 rigidly secured thereon and having an opening through which bar 23 can pass to fit into the flattened portion 23^a of the tubular bar 22. The connecting bracket comprises integral arms 26, one of which is rigidly secured to bar 23. The bars for forming the ends and sides of the structure are the same as those described in connection with Figs. 1 to 3, being adapted to be assembled and locked together by the interfitting slot and tongue-sections. In the connecting brackets at the top of the structure, the bar 23 is shortened so it will terminate close to the top of the arms and side-members. This construction exemplifies one in which the standards are formed of tubular bars and connecting brackets adapted to be readily and slid-

ably connected to provide sectional standards of any desired number.

The invention is not to be understood as restricted to the details set forth, since these may be modified within the scope of the appended 5 claims, without departing from the spirit and scope of the invention.

Having thus described the invention, what we claim as new and desire to secure by Letters Patent is:

1. A set of elements adapted to be assembled into a structure comprising standards, flat metal arms fixed to, and extending horizontally at substantially right angles from, the standards, bars for connecting the arms to form a self-supporting structure, each bar including a plurality of flat metal strips, the side faces of the strips and the arms being adapted to fit together face-to-face, and pairs of interfitting slidably actuatable hooks and slots, each pair of hooks and 15 slots being spaced apart longitudinally for simultaneous connection and adapted to removably secure overlapping ends of the abutting arms and strips against relative transverse movement and in longitudinal alignment to form an 20 elongated vertically rigid connection between the standards.

2. A set of elements adapted to be assembled into a structure comprising inner standard sections provided with only two substantially integral right angled flanges, integral arms secured to the inner faces of said flanges and projecting laterally therefrom at right angles from substantially their vertical centers, and outer connecting standard sections having integral 35 right angled flanges fitting against the outer faces of the flanges on the inner sections above and below the arms, horizontal bars formed of flat metal strips for connecting the arms to form a self-sustaining structure, and detachable 40 connections between the arms and the adjacent ends of the bars, and between the flanges of the inner and outer standard sections, each connection comprising a pair of interfitting slidably actuatable hooks and slots, the hooks and slots of the 45 standard sections being spaced apart vertically, the hooks and slots between the arms and bars being spaced apart horizontally for simultaneous connection at spaced points to secure the overlapping portions of the bars and arms in horizontal alignment and of the standard sections in 50 vertical alignment.
